(57) CLAIM

The ornamental design for a double chambered container with bottom cap, as shown and described.

DESCRIPTION

FIG. 1 is a perspective view of the doubled chambered container with bottom cap according to the present invention.

FIG. 2 is a top view of the double chambered container with bottom cap as illustrated in FIG. 1.

FIG. 3 is a side view of the double chambered container with bottom cap as illustrated in FIG. 1.

FIG. 4 is another side view of the double chambered container with bottom cap as illustrated in FIG. 1.

FIG. 5 is a bottom view of the double chambered container with bottom cap as illustrated in FIG. 1.

FIG. 6 is another side view of the double chambered container with bottom cap as illustrated in FIG. 1; and, FIG. 7 is another side view of the double chambered container with bottom cap as illustrated in FIG. 1.

The broken line showing of a straw in FIG. 1 is for illustrative purposes only and forms no part of the claimed design.
